UNITED STATES PATENT OFFICE.

LYMAN R. ROBERTS, OF RUTHERFORD, NEW JERSEY.

TYPEWRITER.

1,388,203.

Specification of Letters Patent. Patented Aug. 23, 1921.

Application filed August 22, 1917. Serial No. 187,596.

To all whom it may concern:

Be it known that I, LYMAN R. ROBERTS, a citizen of the United States, residing at Rutherford, in the county of Bergen and State of New Jersey, have invented a certain new and useful Improvement in Type-writers, of which the following is a specification.

This invention relates to typewriters and particularly to case-shift mechanism including locking means therefor, which is simple in its construction and operation, and such that there is possible a reduction in the number and complexity of the parts and in the size of the machine without sacrificing any features of durability and efficiency.

With this general object in view, the invention consists in the features, details of construction and combinations of parts which will first be described in connection with the accompanying drawings and then more particularly pointed out.

In the drawings—

Figure 1 is a view in side elevation of a typewriter constructed in accordance with the present invention;

Fig. 2 is a view in end elevation;

Fig. 3 is a fragmentary view in end elevation, with parts broken away and in section;

Fig. 4 is a fragmentary view, in side elevation (enlarged) with parts broken away and in section;

Fig. 5 is a transverse sectional view of the parts shown in Fig. 4.

Fig. 6 is a view, in front elevation, with parts in section;

Fig. 7 is a top plan view and view in side elevation of one of the adjusting rings;

Fig. 8 is a view in perspective of the carriage; and

Fig. 9 is a view thereof in end elevation.

Referring to the drawings, the frame 1 has mounted therein a platen carriage as here shown 22. This carriage is mounted for the usual printing movement by means of grooved rails 23 between which and a grooved carriage guide 20, are a number of ball bearings 21. The platen carriage is also mounted in the frame for case-shift movement. To this end, in the present embodiment the guide 20 is carried by bracket arms 19 extending upwardly from a truck in the form of a rigid plate 18. This plate 18 is secured to the tops of two spaced plungers 15 which are mounted to reciprocate in

the frame 1. To facilitate this movement, the frame is provided with circular recesses 16 for the reception of ball bearings 17.

The plungers 15 are raised by lifting mechanism which is operated by case-shift levers forming part of the key-board. This lifting mechanism in the exemplification here illustrated comprises a liftable member in the form of a cross rod 14 which connects the two plungers 15. Below this cross rod 14, and preferably separate therefrom, is a lifting arm 13 which is keyed to a rock shaft 2 journaled in the frame 1. This shaft is rocked to raise the lifting arm 13 against the cross rod 14 by means of a rocker arm 3 which is also keyed to shaft 2, the shaft being flattened to accommodate a key 4. This arm is located between two case-shaft levers 5 and 6 which are journaled on the shaft 2 but not keyed thereto. The case shift lever 5 is provided with a lug 7 which overhangs arm 3 and displaces the same upon depression of the lever 5. The case shift lever 6 is provided with a lug 8 which bears a similar relation to arm 3. With such a construction, it will be seen that depression of either case-shaft lever displaces arm 3 and rocks the shaft 2, thus causing lifting arm 13 to engage cross rod 14 and elevate the carriage supporting plungers 15. It is noted further that the two case shift levers operate independently of each other.

For holding levers 5 and 6, as well as arm 3, in position, the shaft 2 carries at its outer end a collar 9, secured thereto by pin 10. To normally maintain the arm 3 in elevated position ready for operation, a torsion spring 12 is connected to a collar 11 on the shaft 2 and to the frame 1.

It will be seen that actuation of lifting lever 13 will cause the plungers 15 to be elevated until some part of the lifted or lifting mechanisms engages some stop member. The invention includes means for adjusting the limit of case-shaft movement. This may be accomplished by interposing a varying thickness of metal in the path of rod 14. As here illustrated as an example, secured to the frame in the path of rod 14 is a wedge-shaped ring 28. The ring is adjustably held in place by a screw 30 passing through a slot 29.

For the extreme case-shift, depression of lever 6 causes the lifting lever to raise the plungers until rod 14 engages ring 28. Thus,

this ring acts as a stop or abutment and definitely fixes the throw and movement of the carriage. Should a greater or less movement be desired, the ring is moved on its center to interpose a less or greater thickness of metal in the path of the cross rod.

The invention includes means for varying the throw or movement of the carriage to obtain a different case position. This may

- 10 be accomplished, for example, by interposing a spacing or stop member between the cross rod 14 and the stop ring 28, and in structures embodying the invention to the best advantage, this stop member is placed 15 in operative position by the operation of the case shift lever. Although capable of various constructions, as here illustrated, extending rearwardly from the intermediate case-shift lever 5 is a curved arm 31 carrying 20 a laterally projecting pin 32 riding in a slot 33 in a reciprocating plate 34. This plate is mounted for reciprocating movement by means of a slot 35 riding on alined studs 36. Projecting rearwardly from plate 25 34 is a spacing or stop lug 37 positioned to be interposed between the lifting rod and the stop ring 28. When the intermediate case shift lever 5 is operated, the lifting action, through arm 31, is the same as before, but the 30 limit of the carriage movement is less because as lever 5 is operated, arm 31 swings upwardly and its pin 32, riding up the slot 33, moves plate 34 rearwardly. This interposes the spacing or stop lug 37 between the 35 cross rod and abutment 28 (see dotted lines of Fig. 3). Thus, the lifting movement is definitely limited for an intermediate case position of the carriage. It will be seen that adjustment for this case shift movement is 40 also made by means of the ring 28.

The invention includes a case shift control lever and in structures embodying the invention to the best advantage, this control lever is pivoted to swing transversely of the 45 case shift levers. Although capable of various constructions, in the present embodiment, keyed to a shaft 39 journaled in frame 1 is a control lever 38. Also keyed to the shaft is a bifurcated dog 40, the arms of 50 which are of unequal length (see Fig. 6). The dog 40 may be swung to one side or the other to be brought to a locking position above either case shift lever to hold the same depressed. The arms of dog 40 are of different 55 lengths, because the case shift levers have unequal depressions.

Case shift levers 5 and 6 are provided with finger pads 5' and 6' and are held in normal position by springs 41 and 42 connected to 60 a lug 43 on the frame.

I claim:

1. In a typewriter, a platen carriage, a plurality of case shift levers, lifting mechanism for the carriage operable by either of 65 said case shift levers, an abutment engaged

by part of said lifting mechanism upon operation of one of said case shift levers, a slotted plate having a spacing lug associated therewith, and a pin associated with the other case shift lever to ride in said slot and move the plate to interpose the spacing lug between the lifting mechanism and said abutment upon operation of said last named case shift lever.

2. In a typewriter, a platen carriage, a 75 plurality of case shift levers, lifting mechanism for the carriage operable by either of said case shift levers, an abutment engaged by part of said lifting mechanism upon operation of one of said case shift levers, a 80 slotted plate having a spacing lug associated therewith, a pin associated with the other case shift lever to ride in said slot and move the plate to interpose the spacing lug between the lifting mechanism and said abutment upon operation of said last named case shift lever, and means for guiding the movement of said plate.

3. In a typewriter, a platen carriage, a plurality of reciprocable plungers for elevating the carriage for case shift movement, a cross rod connecting said plungers, a plurality of case shift levers, means operable by either of said levers for lifting said rod, an abutment engaged by said rod upon operation of one of said case shift levers, a slotted plate having a spacing lug associated therewith, and a pin associated with the other case shift lever to ride in said slot and move the plate to interpose the spacing lug between the cross rod and the abutment upon operation of said last named case shift lever.

4. In a typewriter, a platen carriage, a plurality of reciprocable plungers for elevating the carriage for case shift movement, a 105 cross rod connecting said plungers, a plurality of case shift levers, an arm operated by either of said levers, a rock shaft rocked by said arm, a lever on said rock shaft for lifting the cross rod, an abutment engaged by the cross rod upon operation of one of said case shift levers, a slotted plate having a spacing lug associated therewith, and a pin associated with the other case shift lever to ride in said slot and move the plate to interpose the spacing lug between the cross rod and the abutment upon operation of said last named case shift lever.

5. The combination with a frame, of a carriage, means for effecting a case shifting movement of the carriage, an adjusting plate having a broad bearing surface carried by the frame and rotatable with respect thereto to bring varying thicknesses of metal into position to control the case shifting movement.

6. In a typewriter, a carriage, a rigid frame for mounting said carriage, a plunger reciprocable in said frame for imparting case-shift movements to said carriage, a 130

- wedge movable on said frame to provide an abutment of variable thickness between said frame and a part rigid with said plunger to limit the extreme position of the carriage on 5 a case-shift movement, and means interposable between said wedge and a part rigid with said plunger for providing a limit to another case-shifting movement.
7. In a typewriter, a carriage, a rigid frame for mounting said carriage, a plunger reciprocable in said frame for imparting case-shift movements to said carriage, a wedge movable on said frame to provide an abutment of variable thickness between 10 said frame and a part rigid with said plunger to limit the extreme position of the carriage on a case-shift movement, and means interposable between said wedge and a part rigid with said plunger for providing a limit 15 to another case-shifting movement, said case-shifting movements having the same starting position for the carriage.
8. In a typewriter, a carriage, an oscillatory shaft through which case-shifting movements of different extent are transmitted to 20 said carriage, an arm keyed to said shaft, and key levers provided with lugs or projections for engaging said arm on the same side of the shaft.
9. In a typewriter, a carriage, an oscillatory shaft through which case-shifting movements of different extent are transmitted to said carriage, an arm keyed to said shaft, and key levers provided with lugs or projections for engaging said arm on the same side 25 of the shaft, said lugs or projections being at different distances from the axis of said shaft.
10. In a typewriter, a carriage, an oscillatory shaft through which case-shifting movements of different extent are transmitted to said carriage, an arm keyed to said shaft, and key levers provided with lugs or projections for engaging said arm on the same side 30 of the shaft, said levers being coaxial with said shaft.
11. In a typewriter, a platen carriage and a type bar segment, one of which elements is capable of case shift movement, a plurality 35 of case shift levers, lifting mechanism operable by either of said case shift levers, an abutment engaged by part of said lifting mechanism upon operation of one of said case shift levers, a slotted plate having a spacing lug associated therewith, and a pin associated with the second case shift lever to ride in said slot and move the plate to interpose the spacing lug between the lifting
- mechanism and said abutment, upon operation of said second case shift lever. 60
12. In a typewriter, a platen carriage, a support on which the carriage has letter space movement, a main frame having bearing members, a plurality of plungers reciprocating in said bearings and on which said support is mounted for case shift movement, a cross rod connecting said plungers, a plurality of case shift key levers, means operable by said key levers for lifting said cross rod different distances, an abutment associated with the bearing members for engagement by the cross rod to limit the lifting movement upon operation of one key lever, and a spacing member interposable between the cross rod and said abutment for limiting 65 the lifting movement upon operation of the other key lever. 70
13. In a typewriter, a case shifting unit including a platen carriage and a liftable member, an oscillatory shaft through which case shifting movements of different extent are transmitted to the case shift unit, a lifting arm on said shaft for engaging said liftable member, a rocker arm also on said shaft, and case shift key levers provided with lugs or projections for engaging said rocker arm 75 on the same side of the shaft. 80
14. In a typewriter, a frame, a platen carriage and a type bar segment, means for effecting a case shifting movement of one of said elements, and an adjuster plate carried by the frame and having a broad bearing surface and rotatable with respect to the frame to bring varying thicknesses of metal into position to control the case shifting 95 movement. 90
15. In a typewriter, a frame, a case shifting unit including a platen carriage, a support therefor, a plurality of plungers reciprocating in the frame, and a cross rod 100 connecting the plungers, a plurality of case shift levers having lugs thereon, a rocker arm for engagement by said lugs, a rock shaft on which said rocker arm is mounted, a lifting arm on the rock shaft for engaging said cross rod to lift the case shift unit, an abutment associated with the frame for engagement by the cross rod upon operation of one case shift lever, a slotted plate having a spacing lug associated therewith, and a pin associated with the second case shift lever for riding in said slot to interpose the spacing lug between the abutment and the cross rod upon operation of the second case shift lever. 105 110 111
